(57) **CLAIM**

The ornamental design for a pad for an orthodontic bracket, as shown and described.

DESCRIPTION

FIG. 1 is a perspective view of a pad for an orthodontic bracket in a multiple tooth arrangement showing my new design;

FIG. 2 is an enlarged perspective view thereof;

FIG. 3 is an enlarged bottom plan view thereof;

FIG. 4 is an enlarged front elevational view thereof;

FIG. 5 is a right-side elevational view thereof, the left side

being a mirror image thereof;

FIG. 6 is an enlarged top plan view thereof; and,

FIG. 7 is an enlarged rear elevational view thereof.

The broken lines are included for purposes of showing environment and form no part of the claimed design.
